(57) **CLAIM**

The ornamental design for a picture bracelet, as shown and described.

DESCRIPTION

FIG. 1 is a top view of the bracelet; the bottom view being a mirror image.

FIG. 2 is a side view of the bracelet; the front, right, left, and rear views all being mirror images; and,

FIG. 3 is a perspective view of the bracelet. The markings shown in FIG. 3 are merely exemplary.

My new bracelet is characterized by beads with convex transparent tops secured with an elastic cord. Pictures are displayed behind each transparent top.
